EX

OR D 16,077

DESIGN.

W. H. SWANTON.

STOVE OR RANGE.

Patented May 5, 1885.

No. 16,077.

UNITED STATES PATENT OFFICE.

WILLIAM H. SWANTON, OF CAMBRIDGE, MASSACHUSETTS.

DESIGN FOR A STOVE OR RANGE.

SPECIFICATION forming part of Design No. 16,077, dated May 5, 1885.

Application filed March 7, 1885. Term of patent 7 years.

To all whom it may concern:

Be it known that I, WILLIAM H. SWANTON, of Cambridge, in the county of Middlesex and State of Massachusetts, have invented a new 5 and original Design for Stoves and Ranges, of which the following is a specification.

My design for cook-stoves is illustrated in the accompanying cut, in which the figure is a perspective view of a stove embodying the 10 elements of my design.

The top of the stove *a* has a turned-down band around its periphery, as is common in modern cook-stoves. The corners of this band, however, instead of being rounded, are made 15 rectangular. The side of the stove is divided into upper and lower panels by a band extending horizontally around the stove-body, and the corners of this band are also made rectangular. The bottom band of the stove also 20 has rectangular corners. The elevated closet *l* has a turned-down band at top and bottom, and the corners *j j* of these bands are rectangular, as are the corners of the projecting hearth *e* and shelf *f*.

25 The corners of the stove-body *g g* have an ornamental pilaster, the base and capital of which are rectangular, the pilaster being rounded.

The doors are ornamented near their edges

with what is known as a "rope molding" parallel with the edge of the door, said rope molding being between plain beads or bands. 30

What I claim is—

1. The design for a cook-stove body divided into panels by a horizontal band provided with 35 right-angled corners, as shown.

2. In a cook-stove having top band with square corners, the hearth design, also having right-angled corners, as shown.

3. In a cook-stove design in which the body- 40 bands have square corners, the elevated oven having bands with rectangular corners, as shown.

4. In a stove design in which the bands have right-angled corners, the ornamental corner 45 pilaster having rectangular base and capital and rounded body, as shown.

5. In a cook-stove design, the doors having 50 rope moldings parallel with their edges between plain bands, as shown.

In testimony whereof I have signed my name to this specification, in the presence of two subscribing witnesses, this 3d day of March, 1885.

WILLIAM H. SWANTON.

Witnesses:

S. LOUIE HULME,
C. F. BROWN.
